UNITED STATES PATENT OFFICE.

DUDLEY S. HAWKINS, CASSIUS M. METSCH, AND GEORGE HEISLER, OF EAST LIVERPOOL,
OHIO,

DESIGN FOR A VELOCIPED.

54,257.

Specification for Design.

Patented Dec. 9, 1919.

Application filed July 18, 1919. Serial No. 311,888. Term of patent 7 years.

To all whom it may concern:

Be it known that we, DUDLEY S. HAWKINS, CASSIUS M. METSCH, and GEORGE HEISLER, citizens of the United States, residing at East Liverpool, in the county of Columbiana and State of Ohio, have invented a new, original, and ornamental Design for Velocipedes, of which the following is a specification, reference being had to the accompanying drawing, forming part thereof.

Figure 1 is a perspective view of a veloci-

pede showing our new design, looking from one side thereof.

Fig. 2 is a similar view, looking from the other side thereof.

We claim:

The ornamental design for a velocipede, as shown.

DUDLEY S. HAWKINS.
CASSIUS M. METSCH.
GEORGE HEISLER.
